United States Patent Office.

CHARLES EDWARD GIBBS, OF BOSTON, MASSACHUSETTS.

Letters Patent No. 102,803, dated May 10, 1870.

IMPROVEMENT IN COMB-CLEANERS.

The Schedule referred to in these Letters Patent and making part of the same.

To all to whom these presents shall come:

Be it known that I, CHARLES EDWARD GIBBS, of Boston, in the county of Suffolk and State of Massachusetts, have made an invention of a new and useful Improvement in Implements for Cleaning Toilet-Combs, and do hereby declare the following to be a full, clear, and exact description thereof, due reference being had to the accompanying drawings making part of this specification, and in which—

Figure 1 is a perspective representation, and

Figure 2, a section of my invention.

The article upon which this invention is based, as its name implies, is intended to effect the cleaning of toilet-combs, by removing or scraping from between the teeth of such articles, the foreign substances which adhere to and accumulate upon the same, the neatness, if not necessity, of such care of a comb being apparent to all intelligent people.

The class of comb-cleaners to which my present improvement relates, are those in which a series of metallic wires connect and span the extremities of a yoke-shaped or arched metallic bar, the wires being cast or soldered into or upon the metal of said bar, the semi-elastic properties and strength of the yoke serving to maintain the rigidity of the wires and prevent their misplacement under service.

In the construction heretofore of comb-cleaners of the above class, plain, straight wires have been employed, and which are passed up and down in between the teeth.

This invention consists in the adoption, in lieu of the straight wires before mentioned, of a series of corrugated wires, or of wires bent into a helical form, in order to produce, in a given distance, a much greater

cleaning surface than can be obtained with the straight wires before mentioned.

This improvement is particularly valuable in cleaning the interstices at the base of the teeth of the comb, and is to be used in such locality by forcing it backward and forward quickly within such interstices.

The concavities in the wires of my improvement are productive of beneficial results, as compared with a straight wire, as they fit more closely to or cover a much larger portion of the surface of the two.

The accompanying drawings represent at *a* a cast-metal bar, of the shape substantially of a yoke or other analogous or suitable form; the extremities of such bar being prolonged into lateral horizontal feet *b b*, which serve to support a series of corrugated, undulating, or twisted wires *c c*, &c., arranged in the manner of an ordinary gridiron, the ends of such wires being cast in or soldered to the feet *b b*.

One end of the yoke or bar *a* may be provided with an integral handle, *d*, for convenience in use, although this handle is not a necessary feature in the device.

The low cost and durability of a comb-cleaner produced as above explained adds to its value.

Claim.

I claim an implement for cleaning combs, composed of a series of metallic corrugated or undulating wires, cast into or soldered to a metallic yoke or other suitable frame, in the manner shown and set forth.

CHAS. EDWARD GIBBS.

Witnesses:

FREDERICK CURTIS,
EDWARD GRIFFITH.
